UNITED STATES PATENT OFFICE.

HERBERT W. DAY, OF WOLLASTON, MASSACHUSETTS.

SPRAY NOZZLE.

Application filed June 2, 1919. Serial No. 301,273.

To all whom it may concern:

Be it known that I, HERBERT W. DAY, a citizen of the United States, residing at Wollaston, county of Norfolk, State of Massachusetts, have invented an Improvement in Spray Nozzles, of which the following description, in connection with the accompanying drawing, is a specification, like characters on the drawing representing

10 like parts.

This invention relates to spray nozzles and to a method of spraying therewith, and has for one of its objects to provide a novel spray nozzle and novel method of spraying 15 by which a spray of a predetermined shape will be produced which will remain constant even though the pressure under which the fluid or fluids are being delivered varies.

20 This invention also has for its object to provide a novel spray nozzle which will deliver a spray having a uniform consistency throughout its extent so that the character of the mixture at the edge of the 25 spray will be the same as that at the center of the spray.

Other objects of my invention are to improve spray nozzles in various ways, all as will be more fully hereinafter set forth.

30 In order to give an understanding of my invention, I have illustrated in the drawings a selected embodiment thereof which will now be described, after which the novel features will be pointed out in the 35 claims.

In the drawings, Fig. 1 is a central sectional view through a spray nozzle embodying my invention;

Fig. 2 is a bottom plan view of Fig. 1 40 with a portion broken out;

Fig. 3 is an end view;

Fig. 4 is a section on the line 4—4, Fig. 1.

Fig. 5 is a cross sectional view through the spray taken on substantially the line 45 5—5 Fig. 1 and indicating the shape of the spray.

My improved spray nozzle comprises a body portion 1 having separate chambers or spaces 2 and 3 into which the different 50 fluids or gases to be sprayed are delivered, a head 4 having a delivery orifice 5 through which the spray is delivered from the nozzle, and a plurality of converging ducts or passages leading from the separate chambers 55 2 and 3 to the delivery orifice 5. These ducts or passages and the delivery orifice

5 have such a relation to each other that the streams issuing from the ducts or passages meet in the plane of the orifice 5. I 60 find that by means of this construction a spray will be produced which has a predetermined cross sectional shape that does not vary even though the pressure under which the fluids or gases entering the chambers 65 2 and 3 vary.

Any number of these converging ducts or passages may be employed. In the construction herein shown I have provided two ducts or passages 6 which communicate with the chamber 2 and one duct or passage 7 70 communicating with the chamber 3. The duct or passage 7 is shown as situated axially of the nozzle, and the passages 6 are on either side of the passage 7 and converge toward the orifice 5. This arrangement of passages is however, merely used

for illustrative purposes, as the invention is not limited to any particular number of such passages. It is, however, important 75 that said passages should have such relation to each other, and to the orifice 5 that the streams of fluid or gas issuing from

said passages will meet in the plane of the orifice 5 or, in other words, in the plane of the dotted line 8 which is employed to 80 indicate the plane of the orifice. The streams issuing from the passages 6 and 85 7 are released from the nozzle at the plane of the orifice 5, and this is the point at which they meet. My invention, therefore,

85 provides a construction in which the various streams meet and are released from the nozzle at the same point. By having these various streams meet at a common 90 point in the plane of the orifice through 95 which they are released from the nozzle, I

find that the spray projected from the nozzle will have a form determined by the projection of the axes of the several streams of fluid beyond their common point of intersection, and that said spray will be bounded by a surface formed by the continuation beyond the orifice of the outer 100 side of the wall of each of the intersecting ducts or passages, and by outer side as

used above I mean that side of each duct or passage situated furthest from the central axis of the spray.

A spray thus produced will have a cross-sectional shape similar to the shape of the 110 delivery orifice, and this cross-sectional shape of the spray will remain constant at

all distances from the nozzle, and even though the pressure of the fluid or gas varies.

In the construction illustrated the orifice 5 has an oblong shape with rounded ends, and the cross-sectional shape of the spray at all points thereof will have a similar shape as indicated in Fig. 5.

Furthermore, this construction provides 10 a spray which has a sharp well-defined periphery or edge, and there is an entire absence of scattering drops around the edge of the spray. Moreover, this construction will produce a spray which is of uniform 15 consistency or density throughout its cross-sectional area, so that if a liquid is being sprayed, the moisture at the center of the spray and at the outside edge will be of the same amount or degree.

20 The body 1 may be constructed in various ways without departing from the invention. In the construction shown, the body is provided with a side opening 9 leading to the chamber 2 so that by screwing a pipe into 25 said opening 9 a liquid or gas may be delivered to the chamber 2. The chamber 3 is also provided with an opening 10 to which a pipe may be connected, and through which gas or liquid may be delivered thereto.

30 The head 4 is shown as made separate from the body 1 and as being screw-threaded thereto at 11. The chamber 3 is shown as being formed from a short length of tubing or pipe which is screwed into the head 4 and extends axially through the body 1. This construction, however, is adopted as 35 one convenient way of making the head, and the construction of the latter may be varied in various ways without departing 40 from the invention.

In using the spray nozzle, the liquid may be introduced into the chamber 2 and a gas under pressure into the chamber 3, or a liquid may be introduced into the chamber 45 3 and a gas into the chamber 2. In either case the spray which is produced will have the characteristics above described.

The spray nozzle can also be used for 50 mixing two liquids by introducing the two liquids to be mixed into the chambers 2 and 3, respectively, under pressure.

While I have illustrated a selected embodiment of my invention, I do not wish to be limited to the constructional features 55 shown.

Having thus described my invention what I claim as new and desire to secure by Letters Patent is—

1. A spray nozzle having a body provided 60 with two separate chambers, and a head provided with a delivery orifice and a plurality of separate non-coaxial ducts or pas-

65 sages, all of which are so disposed that the axes thereof meet in the plane of the orifice, some of said passages connecting with one chamber and the remainder thereof connecting with the other chamber, whereby the non-coaxial streams issuing from said ducts meet in the plane of the orifice, and at the 70 point at which they are released from the nozzle, and thereby become thoroughly mixed at the releasing point to form a spray having a definite shape.

2. The method of spraying fluid through 75 the delivery orifice of a spray nozzle, which consists in projecting through said orifice a plurality of streams of fluid from different sources, said streams having different axes which are so disposed that they all meet at a common point in the plane of the orifice, and at the point at which they are released from the nozzle, whereby the streams are thoroughly mixed at said point of release 80 and the shape of the spray is controlled.

3. The method of producing a spray by 85 commingling a plurality of separate streams of fluid, which method consists in bringing together at a common point a plurality of non-coaxial streams of fluid from different sources, and releasing said commingling streams in the form of a spray of predetermined shape at such common point.

4. A spray nozzle having a body provided 90 with two separate chambers and a head provided with a delivery orifice and a plurality of ducts or passages connecting said orifice with one chamber and another duct or passage connecting said orifice with the other chamber, said ducts or passages being non-coaxial and all of them being so disposed 95 that the axes meet in the plane of the orifice, whereby the non-coaxial streams issuing from said ducts meet in the plane of the orifice and at the point at which they are released from the nozzle and thereby become 100 thoroughly mixed at the releasing point to form a spray having a definite shape.

5. The method of spraying fluid through 105 the delivery orifice of a spray nozzle, which consists in projecting through said orifice a plurality of streams of fluid from one source and another stream from another source, said streams having different axes 110 which are so disposed that they all meet at a common point in the plane of the orifice and at the point at which they are released from the nozzle, whereby the streams are thoroughly mixed at said point of release 115 and the shape of the spray is controlled.

120 In testimony whereof, I have signed my name to this specification.

HERBERT W. DAY.
